UNITED STATES PATENT OFFICE.

WILLIAM J. WALKER, OF CHICAGO, ILLINOIS, ASSIGNOR TO THE CHICAGO FOLDING BOX COMPANY, OF SAME PLACE.

PAPER BOX.

SPECIFICATION forming part of Letters Patent No. 591,148, dated October 5, 1897.

Application filed December 5, 1896. Serial No. 614,550. (No model.)

To all whom it may concern:

Be it known that I, WILLIAM J. WALKER, a citizen of the United States, residing at Chicago, in the county of Cook and State of Illinois, have invented a certain new and useful Improvement in Paper Boxes, which is fully set forth in the following specification, reference being had to the accompanying drawings, in which—

10 Figure 1 is a plan view of the blank of which my box is made. Fig. 2 is a plan view with the box partly struck up. Fig. 3 is a plan view with the box still further struck up. Fig. 4 is an end elevation of the box in the condition shown in Fig. 3. Fig. 5 is a similar end elevation showing the end flaps folded in. Fig. 6 is a similar end elevation showing the complete box. Fig. 7 is a vertical longitudinal section on the line 7 7 of Fig. 5. Fig. 20 8 is a vertical cross-section on the line 8 8 of Fig. 7. Fig. 9 is a vertical cross-section similar to that of Fig. 8, but showing the box completely struck up and the cover down. Fig. 10 is a view of the bottom of one end of the 25 box, looking in the direction of the arrow 10 of Fig. 7.

My invention relates to paper boxes, and has for its object to provide a box to be made from a single blank, easily struck up, secure 30 when so struck up, and formed with a minimum waste of stock. I obtain this object particularly by the employment of the locking devices hereinafter shown and described.

Referring to the drawings by letter, and particularly to Fig. 1, A represents the bottom of the box; B, one side thereof; C, the remaining side, and D the top or lid hinged to the side C. These four parts are all shown of the same size, but this is not necessary unless the box is to be square in cross-section. The bottom A is provided at each end with a flap a. In each flap a, near the outer edge thereof, is formed a slot a', parallel to the said edge. The side B is provided at each end 40 with a flap b. The side C is provided at each end with a flap c. Each such flap upon that side adjacent to the side a carries a tongue c', which is preferably formed by being cut out from the said flap a. The corresponding 45 50 notch thus formed in the flap a has nothing to do with the operation of the box or its

lock and need not be lettered or described. To each flap c, moreover, upon the side farthest from the flap a, is hinged a second flap c² of the same size and shape. Out of the 55 flap c² there is cut a tongue c³, so that the same shall be hinged to the adjacent edge of the flap c. The aperture thus formed in the flap c² has nothing to do with the operation of the box or its lock and need not be lettered or described. All of the end flaps a, b, c, and c² are preferably of the same size and shape, the first three all overlying one another to form the end of the box. The top or lid D is not provided with end flaps, but is provided 65 with a narrow side flap d, hinged to its outer or free edge.

The operation of these locking devices will best be understood from a description of the method in which the box is struck up. The 70 side B is first turned up at right angles with the bottom A, the end flaps a are turned up at right angles to the bottom A and to the now vertical side B, and the end flaps B are swung in against the end flaps a. This position of the parts is shown in Fig. 2. The side 75 C is now swung up at right angles to the bottom A, carrying with it the attached end flaps and the top D. This position of the parts is shown in plan in Fig. 3 and in end elevation 80 in Fig. 4. The end flaps c are now swung in against the end flaps b in the direction of the arrows of Fig. 3, carrying with them the end flaps c². This position of the parts is shown in end elevation in Fig. 5. Each tongue c³ is 85 now swung inward over the upper edge of the end flaps b and a and is inserted through the slot a' from the inside of the box outward, so that the end of the tongue lies and is held between the end flap a and the end flap b. This 90 position of the tongue c³ is particularly illustrated in Fig. 7. The short tongue c', which now projects downward from the end of the bottom of the box, is swung around and tucked between the end flap a and the end 95 flap b, as is particularly shown in Figs. 7 and 10. The box in this condition is ready for receiving its contents. When the box is to be closed, the two end flaps c², which as yet remain in a vertical position, are swung down 100 into a horizontal position, the lid D is likewise swung down, and the flap d inserted inside of

the box, as particularly shown in Fig. 9. The box is then in its completed form, as shown in end elevation in Fig. 6.

It will be obvious that certain modifications 5 of the structure hereinabove described may be made without departing from the spirit of my invention. Thus, for example, the end flaps c^2 may be altogether omitted, the flap c being provided merely with the tongues c' and c^3 . Again, the cover D might be otherwise secured to the body of the box or might be altogether separate therefrom without interfering with the operation of the locking devices of the ends. Finally, many changes 15 may be made in the relative size and form of the parts, the shape of the tongues, &c., without altering substantially the mode of operation.

Having thus described my invention, what 20 I claim, and desire to secure by Letters Patent, is—

1. In a knockdown paper box, the bottom A, with end flaps a , provided with slots a' ; the side B, with end flaps b ; and side C, with 25 end flaps c , said end flaps being provided with tongues c^3 adapted to be tucked through the slots a' and between the flaps a and b when the box is struck up.

2. In a knockdown paper box, the bottom 30 A, with end flaps a , provided with slots a' ; the side B, with end flaps b ; and side C, with end flaps c , said end flaps being provided with tongues c^3 adapted to be tucked through the

slots a' , and with tongues c' adapted to be tucked between the bottom edges of the end 35 flaps a and b , when the box is struck up.

3. In a knockdown paper box, the bottom A, with end flaps a , provided with slots a' ; the side B, with end flaps b ; and side C, with end flaps c and c^2 , the said end flaps c being 40 provided with tongues c^3 adapted to be tucked through the slots a' , and with tongues c' adapted to be tucked between the bottom edges of the end flaps a and b , when the box is struck up. 45

4. In a knockdown paper box, the bottom A, with end flaps a , provided with slots a' ; the side B, with end flaps b ; the side C, with end flaps c and c^2 , the said end flaps c being provided with tongues c^3 adapted to be tucked 50 through the slots a' , and with tongues c' adapted to be tucked between the bottom edges of the end flaps a and b , when the box is struck up; and the lid D hinged to the side C and provided with a side flap d. 55

5. In a knockdown paper box, the bottom A having the end flaps a ; with the side B having the flaps b ; and the side C having the end flaps c provided with the tongues c' projecting from the bottom edges adapted to be inserted between the flaps a and the flaps b , when the box is struck up. 60

WILLIAM J. WALKER.
